DOOR CHECK BRACKET

John Hines, South Norwalk, Conn., assignor to
Norwalk Lock Company, New York, N. Y., a
corporation of Connecticut

Application December 3, 1945, Serial No. 632,375

6 Claims. (Cl. 248—291)

1

The invention is a door check and the dominant object thereof resides in the provision of novel and swiveled means to insure proper alignment of the door check to preclude binding thereof during opening or closing of the door. The invention has as another object to provide an improved compensatory apparatus carrying the door check for automatically lining up the door check due to improper mounting of the door or improper mounting of the door check. The invention has as a further object the provision of a serviceable expansion cup to sustain the piston of an air pump employed in the door check in seal tight engagement with the bore of the cylinder of the pump during reciprocation of the piston on opening and closing of the door. Other objects, advantages and features of the invention will be apparent from the following detailed description taken with the accompanying drawings wherein;

Fig. 1 is a front elevational view of the door check according to my invention shown mounted on the jamb of the door and on the latter, however showing the door closed but adapted to be swung rearwardly.

Fig. 2 is an enlarged horizontal sectional view on the line 2—2 of Fig. 1, shown partly broken away.

Fig. 3 is an enlarged sectional view on the line 3—3 of Fig. 2.

Fig. 4 is an enlarged fragmentary view of Fig. 2.

Figs. 5 and 6 are longitudinal and transverse sectional views on the lines 5—5, and 6—6 respectively of Fig. 2.

Fig. 7 is a perspective view of the expansion cup.

Fig. 8 is a horizontal sectional view on the line 8—8 of Fig. 3.

Fig. 9 is a sectional view on the line 9—9 of Fig. 3 indicating the neutral relation of the swiveled yoke at a time when the door is closed.

Fig. 10 is a view similar to Fig. 9 but illustrating the swiveled yoke cocked when the door is fully opened, and

Fig. 11 is a horizontal sectional view on the line 11—11 of Fig. 3.

Referring to the drawings, the door check C includes the air pump A, the spring recoil device or brake R, the swiveled connection S, and the bracket B.

The pump A comprises a cylinder 10 having the circular bore 11 slidably guiding the piston head P to which is attached the piston rod 12 reciprocably guided in the cap 13 appropriately fastened in seal tight relation to one end of the cylinder.

2

Threadably and removably connected to the other end of the cylinder is the cap 14 integrally carrying boss 15 sustaining fulcrum pin 16 on which the ears 17 of the bracket B are swingably retained. By such arrangement ears 17 straddle boss 15 and are hingedly associated with the latter. Consequently if the bracket is held in a fixed relation the pump A may be swung relative to the bracket. In actual practice, however, the base 18 of the bracket is secured to a swinging door D by fastening means such as screws (not shown) fitting into the openings 19.

Rotatably and adjustably mounted on the boss 15 is the threaded valve 20 having the tapered end or valve head 21 adapted to open and close the orifice 22 which is in communication with bore 11 of the cylinder 10. Specifically the knurled head 23 of the valve may be rotated for positioning the valve head 21 against the valve seat 24 or away therefrom. The valve includes a relatively smooth portion 25 which is adapted to open and close orifice 26 which in turn is in communication with orifice 22. Thus by controlling the knurled head 23 it is possible to regulate the volume of air that may be drawn into the cylinder or casing 10.

Locking means is provided to hold the knurled head 23 of the valve in a set position. For this purpose the pointed end 27 of a slidably guided tumbler 28 is utilized to disengageably interlock with the teeth of the knurled rim of the head 23 and such action is sustained by the confined and concealed spring 29 normally urging the tumbler 28 towards the head 23.

The piston head P comprises an annular metal disc 30, a primary cup 31 which may be of leather or felt, a supplementary spring cup 32 nested in cup 31, a washer 33, and a nut 34, all mounted on the reduced stem 35 of the piston rod 12, the arrangement being such that clamping action of the nut 34 on the threaded stem 35 holds the washer 33 clamped against spring cup 32 which in turn holds the felt or leather cup 31 clamped against disc 30 and the latter against shoulder 36 of the piston rod 12.

The nested and metal cup 32 has its annular and tapered rim 37 provided with a plurality of tapering slots 38 to define spaced and resilient outwardly inclined or diverging resilient fingers 39 coacting with the annular rim 40 of the felt or leather cup 31 to desirably hold the latter in seal tight sliding or reciprocating engagement with the bore 11 of the cylinder 10 as the piston rod 12 is reciprocated. Each slot has its narrow portion at the outer margin of the rim 37 and its

widest portion at the base 37' of the cup 32, the widest portions merging with the spaced notches 38' along the outer edge of base 37'.

The piston rod 12 extends into and is also threadably connected to the crank or elbow 41 having its lower arm 42 provided with the irregularly or partly non-circular shaped opening 43 (Fig. 2) closely receiving and interlocking with a similarly shaped shaft 44 rotatably guided in the bearings or circular openings 45 and 46 in the spaced arms 47 and 48 of the U shaped oscillatable or swiveled yoke Y having its base or intermediate portion 49 provided with the arcuate portions or cams 50 defining the irregularly shaped opening 51 receiving the squared shaped head or boss 52 of the threaded bolt 53.

The square shaped head 52 is spot welded to the bracket 54 and thus is fixedly carried by the latter. Surrounding the threaded shank 54' of the bolt is the annular washer 55 adapted to be clamped against the flat face 56 of the boss 52 by the nut 57. By the arrangement disclosed, yoke Y may be rotatably rocked or swiveled on the square shaped boss 52 which in fact characterizes fulcrum means for the cams 50 of the intermediate arm 49 which is rotatably guided between the washer 55 and the bracket 54. It follows that if the door be rotated or swung towards or away from the jamb J, yoke Y may be tilted relative to the jamb or to the fixed bracket or support 54.

As previously stated the irregularly shaped shaft 44 is locked or keyed to the crank 41 and if the latter is driven shaft 44 is rotated. This shaft is also rotatably guided in the circular bore 57' of the hollow gear 58 and extends downwardly therethrough and through the depending skirt 59 of the gear and downwardly through an irregularly shaped opening 60 of a mount 61 appropriately seated on arm 48 of the yoke Y and having its annular flange 62 confined in the annular housing 63 interposed between the arms 47 and 48 of the yoke. Since shaft 44 is thus also keyed to the mount 61, rotation of the crank arm 41 causes the rotation of mount 61.

The hollow mount 61 is provided with a cut-away part 64 adapted to receive a reflexed end 65 of the lowest coil 66 of the helicoidal spring 67 or in other words this spring is locked to the mount 61 and if the latter is rotated, the spring is wound up in that the upper coil 68 has its reflexed terminal 69 retained against a lip 70 of the bayonet slot 71 in the annular skirt 59 depending from the gear 58. Set screws as 72 and washers 73 prevent vertical displacement of the rotatable shaft relative to the yoke Y.

Normally spring 67 is under some tension, that is, wound up although not fully. This is accomplished by applying a suitable wrench to the rotatable gear 58, thus tensioning or compressing the upper part of the spring. The swiveled dog 74 is then interlocked with the gear 58 to prevent accidental rotation of the latter. If shaft 44 is driven by the crank 41, the keyed mount 61 is rotated, hence winding up the lower part of spring 67. This action takes place when the door D is swung open, that is, the spring is placed under additional tension and the latter is utilized to automatically close the door. As a collateral observation, it should be noted that a tubular member 75 loosely surrounds shaft 44 and is interposed between the mount 61 and the skirt 59. This tubular member limits the extent to which the thrust imparting spring 67 may be compressed.

In mounting the door check for controlling the closing of the door, the wings 76 of the bracket or support 54 are appropriately fastened to the jamb or frame J of the swingable door D and the swingable bracket B is fastened to the door. On opening of the door, the piston head P is shifted in the cylinder 10 away from cap 14, thus air is drawn into the cylinder through the orifices 26 and 22. At this time the piston rod 12 is progressively projected out of the cylinder 10 thus rotating crank arm 41, consequently rotating shaft 44 of the brake or recoil device R. It follows that the tension spring 67 is further compressed.

During the tensioning of the spring 67, yoke Y is transversely rocked relative to the support 54, that is slightly rotated from its neutral position shown in Fig. 9 towards an offset position illustrated in Fig. 10, thus precluding binding of the door and provide for uniform operation of the door check, thereby prolonging the latter's life. Or in other words, the swiveled connection S compensates for the irregularities or misalignments in mounting the door or the check on the door and jamb. As the piston rod is projected from the cylinder air is drawn from the atmosphere past the adjustable bleeder valve 20 and into the cylinder and air in the cylinder is exhausted through the clearing vent or orifice 77 (Fig. 1).

After opening of the door and manual release thereof, the recoil of spring 67 is utilized to automatically close the door. Thus shaft 44 is rotated or retracted to its normal position or predetermined relation and consequently crank arm 41 retracts the swiveled yoke Y which automatically tilts back to its neutral position and the piston is again disposed adjacent the cap 14. On the return stroke of the piston, the door is checked from abruptly closing. This checking action is pneumatic since on the return stroke of the piston, a slight amount of air only is discharged through the clearing vent 77 and the remainder of the air within the cylinder 10 is compressed and gradually exhausted through the orifices 22 and 26, thus providing a cushioning effect.

By reason of the swiveled or pivoted relation between the yoke Y and the fixed bracket 54, involuntary misalignment of the door check is compensated for, or in other words, the swiveled connection S between the brake carrying yoke Y and the fixed bracket 54 characterizes a loose connection to prevent binding of the door check, thus enhancing its life.

The brake or recoil device and the air pump A are of conventional type and have been generally set out herein for purposes of disclosing their association with the novel swingable brake carrying yoke to prevent binding of parts of the door check and with the split resilient cup 32 for insuring a seal tight relation of the piston head with the cylinder 10.

Briefly recapitulating, the door check may be said to comprise the braking device and the pump and the invention herein described in fact is a compensatory apparatus to sustain the braking device of the door check wherein the pump thereof is pivotally associated with the hinged door, the compensatory apparatus having the swiveled or pivoted connection defined in part by the square shaped head or fulcrum means 52 of the threaded bolt 53 fixedly carried by the support 54. Forming a part of this swiveled connection are the plurality of cams 50 bounding the irregular shaped opening 51 or in other words, opening 51 has a peripheral wall embodying the cam

means 50, the latter obviously being a part of the base 49 of the swiveled yoke or carrier means Y. The swiveled connection tiltably holds or sustains the carrier means Y relative to the support 54 and such connection is maintained or retained by the clamping means 57 acting on washer 55 by precluding base 49 from slipping off the fulcrum means 52.

Various changes may be made in details of construction and arrangement of parts without departing from the spirit of the invention or sacrificing any of the advantages thereof inherent therein.

I claim:

1. In a compensatory apparatus to sustain a braking device of a door check wherein a pump is pivotally associated with a door hinged relative to the jamb of said door, a support mounted on said jamb and characterizing bearing means, a yoke having spaced arms for sustaining said braking device and having a base juxtaposed and displaceable relative to said bearing means, said base having an opening bounded by a peripheral wall having convex surface means, fulcrum means fastened to said support and having a portion disposed in said opening and having rectilinear means cooperating with said convex surface means to tiltably sustain said yoke relative to said bearing means, and means mounted on said fulcrum means and cooperating with said yoke to retain said base in close juxtaposition with said bearing means.

2. In a compensatory apparatus to sustain a braking device of a door check wherein a pump is pivotally associated with a door hinged relative to the jamb of said door, a support mounted on said jamb and characterizing bearing means, a yoke having spaced arms for sustaining said braking device and having a base juxtaposed and displaceable relative to said bearing means, said base having an opening bounded by a peripheral wall having a plurality of convexed portions, fulcrum means fastened to said support and having a polygonal head comprising rectilinear faces disposed in said opening and cooperating with said convexed portions to tiltably sustain said yoke relative to said bearing means, and means mounted on said fulcrum means and cooperating with said yoke to retain said base in close juxtaposition with said bearing means.

3. In a compensatory apparatus to sustain a braking device of a door check wherein a pump is pivotally associated with a door hinged relative to the jamb of said door, a support mounted on said jamb, a yoke adjacent said support and having spaced arms for sustaining said braking device and having a base including an opening bounded by a wall having convex surfaces, and a bolt carried by said support and having rectilinear fulcrum means projecting into said opening and cooperating with said surfaces to tiltably sustain said yoke relative to said support.

4. In a compensatory apparatus to sustain a braking device of a door check wherein a pump is pivotally associated with a door hinged relative to the jamb of said door, a support mounted on said jamb, a yoke having spaced arms for sustaining said braking device and having a base including an opening bounded by a wall having arcuate portions, a bolt secured to said support and having a head provided with a polygonal periphery projecting into said opening and cooperating with said arcuate portions to tiltably hold said yoke relative to said support, and means mounted on said bolt for retaining said yoke adjacent said support.

15 5. In a compensatory apparatus to sustain a braking device of a door check wherein a pump is pivotally associated with a door hinged relative to the jamb of said door, a support mounted on said jamb, a yoke having spaced arms for straddling and sustaining said braking device and having a base including an opening bounded by a peripheral wall having a plurality of arcuate portions, a bolt secured to said support and having a rectangular shaped head projecting into said opening and cooperating with said arcuate portions to tiltably sustain said yoke relative to said support, and means mounted on said bolt for retaining said yoke adjacent said support.

20 6. In a compensatory apparatus to sustain a braking device of a door check wherein a pump is pivotally associated with a door hinged relative to the jamb of said door, a support mounted on said jamb, a yoke adjacent said support and having spaced arms for sustaining said braking device and having a base including an opening bounded by a peripheral wall having a plurality of arcuate faces, fulcrum means fixedly carried by said support and having a portion provided with a plurality of rectilinear faces and surrounded by and cooperating with said arcuate faces to tiltably sustain said yoke relative to said support, and means to retain said yoke adjacent to said support.
